UNITED STATES PATENT OFFICE

152,435

DESIGN FOR A VACUUM PACKAGING MACHINE

Theodor M. Reimers, Chicago, Ill., assignor to
Standard Cap and Seal Corporation, Chicago,
Ill., a corporation of Virginia

Application May 26, 1947, Serial No. 139,292

Term of patent 7 years

(Cl. D55—1)

To all whom it may concern:

Be it known that I, Theodor M. Reimers, a citizen of the United States, residing at Chicago, county of Cook, and State of Illinois, have invented a new, original, and ornamental Design for a Vacuum Packaging Machine, of which the following is a specification, reference being had to the accompanying drawings, forming part thereof.

In the drawings, Figure 1 is a front perspective view of a vacuum packaging machine showing my new design;

Figure 2 is an end perspective view of the vacuum packaging machine shown in Figure 1.

The rear of the machine, not shown, is substantially like the front shown.

I claim:

The ornamental design for a vacuum packaging

machine, substantially as shown and described.

THEODOR M. REIMERS.
